DESIGN FOR AN ASH TRAY

Sydney Lodell Wilson, Shelby, Miss.

Application May 25, 1948, Serial No. 146,566

Term of patent 14 years

(Cl. D85—2)

To all whom it may concern:

Be it known that I, Sydney Lodell Wilson, a citizen of the United States of America, residing at Shelby, in the county of Sunflower and State of Mississippi, have invented a new, original, and ornamental Design for an Ash Tray, of which the following is a specification, reference being had to the accompanying drawing, forming a part thereof, wherein:

Fig. 1 is a perspective view of an ash tray, showing my new design.

Fig. 2 is a top plan view.

Fig. 3 is a side elevational view thereof.

Fig. 4 is a view similar to Fig. 3, looking at the opposite side of the ash tray.

Fig. 5 is a view of one end of the ash tray.

Fig. 6 is a view of the opposite end of the ash tray.

Fig. 7 is a longitudinal section, taken on the line 7—7 of Fig. 2.

Fig. 8 is a transverse sectional view taken on line 8—8 of Fig. 2.

Fig. 9 is a transverse sectional view, taken on line 9—9 of Fig. 2.

Fig. 10 is a sectional view, taken on line 10—10 of Fig. 2.

I claim:

The ornamental design for an ash tray, as shown.

SYDNEY LODELL WILSON.
